UNITED STATES PATENT OFFICE.

FRIEDRIG H. STOEHREL, OF READING, PENNSYLVANIA, ASSIGNOR TO THE NOLDE & HORST CO., OF READING, PENNSYLVANIA, A CORPORATION OF PENNSYLVANIA.

STRIPING AND EMBROIDERING MECHANISM FOR KNITTING-MACHINES.

1,008,752.

Specification of Letters Patent. Patented Nov. 14, 1911.

Application filed October 26, 1909. Serial No. 524,647.

To all whom it may concern:

Be it known that I, FRIEDRIG H. STOEHREL, a citizen of the United States, and a resident of the city of Reading, in the county of Berks and State of Pennsylvania, have invented certain new and useful Improvements in Striping and Embroidering Mechanism for Knitting-Machines, of which the following is a specification.

10. My invention relates particularly to straight-bar knitting machines of the "Cotton" type, and consists in an improved embroidery-thread mechanism therefor, as hereinafter fully described in connection 15 with the accompanying drawings and specifically pointed out in the claims.

The main object of the invention is to enable striping on one or more needles, and embroidery designs with or without stripe 20 effects, to be satisfactorily produced as desired in a simple and automatic manner, as will fully appear in the detailed description following.

Figure 1 is mainly an end elevation but 25 showing certain parts in cross-section, of a machine embodying my invention in preferred form. Fig. 2 is a front elevation of an end portion of one of the knitting sections of this machine. Fig. 3 is a plan view, 30 to an enlarged scale, showing a portion of one of my removable embroidery attachments in operative position on the machine; the forward position of the embroidery thread carriers, relative to the knitting, being indicated in dotted lines. Fig. 4 is a 35 diagrammatic view, indicating by a heavy dotted line a full cycle of the embroidery-thread carrier movement, effected by the mechanism described in coöperation with 40 the knitting mechanism. Figs. 5 and 6 are separate views of the thread carrier, in elevation and cross-section.

Certain main features of an ordinary straight-bar knitting machine are indicated 45 in the drawings, so as to clearly show the coöoperative relations of my improvements. The knitting needles 21 fixed in needle-bar 22, knocking-over bits 23, dividers 24, and sinkers 26, operate as usual to produce a 50 plain web 28 from the thread 27, and fur-

ther description of them and other machine features ordinarily employed in plain knitting is unnecessary. My improvements relate to the additional mechanisms provided for the purpose of satisfactorily controlling 55 an embroidery-thread or threads 30 which are to be acted upon by this well known knitting mechanism so as to produce ornamental stripe or design effects; which additional mechanisms will now be fully described.

The embroidery-threads 30, as indicated, are guided in a series of thread-carriers 1 secured to a carrier frame 2, which frame is also provided with a corresponding number 65 of carrier posts for bobbins 29 and with suitable tension devices 33, 34 on a guide rod 32. Trunnion ends 11 on the rear longitudinal bar 12 of each of these frames 2 are pivotally mounted in the forked upper 70 ends of a pair of carrier arms 13 fixed to a rock-shaft 14 which extends the full length of the machine and is adapted to receive a frame 2 for each knitting section of the latter; while the forward longitudinal frame 75 bar 31 is carried upon lifting arms 3 fixed to a shaft 4 mounted in bearings 5 on the machine frame 6. Each carrier frame 2, with its bobbins 29 and thread-carriers 1, is thus operatively attached to the machine 80 so as to be readily removable when desired; and a convenient support for the removed frames is furnished by providing on the machine a longitudinal carrier rod 87 upon 85 which they may be hung out of the way as indicated in dotted lines in Fig. 1.

A forward and rearward movement of the carrier-frame 2, relative to the row of knitting needles 21, is imparted by means of a 90 suitably guided connecting rod 18 pivoted to a bearing pin 17 in the fixed arm 16 of the rock-shaft 14; while vertical movement is imparted by said lifting arms 3 to the forwardly located thread carriers 1, by means of a connecting rod 8 attached to a 95 fixed arm 7 on the shaft 4; suitable cams, 8^a and 20^a being provided on the main cam shaft 78 indicated in Fig. 2 to operate the respective connecting rods 18 and 8; said rod 18 however being indirectly operated 100

by means of a suitably pivoted cam-lever 20 adapted to be thrown into or out of action by a clutch mechanism as hereafter described.

- 5 The embroidery-threads 30 are properly carried to and fro between the knitting needles 21 by the combined forward and rearward and vertical movements of the thread-carriers 1 above described. In order to secure proper engagement of the threads with one or more of the needles as required to produce stripes of any desired widths, or figure designs with or without stripes, as may be desired, I provide mechanism for imparting determined lateral movements to the carriers, parallel with the line of knitting needles, and also for intermitting the forward and rearward movements of the thread carriers, as will now be described.
- 10 20 The rock shaft 14, with the carrier frames 2 thereon is so mounted as to be capable of longitudinal movement whereby the thread-carriers 1 will be moved parallel with the row of needles 21. The time and extent of these movements is determined, as shown, by a pattern-chain mechanism comprising a pattern-wheel 41 which is rotatably mounted on a shaft 39, located below and parallel with the rock shaft 14 at one end of the machine. This pattern-wheel shaft 39 is slidable longitudinally in fixed bearings 36, 37; and the pattern-wheel 41, which carries a chain 55, is provided with a ratchet wheel 41^a which is driven by a pawl 45 carried by an arm 47 pivoted on the shaft 39 and operated through a cam lever 75 and connecting rod 74 by a suitable cam on the cam shaft 78. The pattern-chain wheel and its operating parts are located between fixed 25 30 35 40 45 50 55 60 65 70 75 80 85 90 95 100 105 110 115 120 125 130 collars 40 and 40^a on the shaft 39; said collar 40 as shown having an upwardly extending arm engaging a guide rod 59 and carrying a chain support 56 and an anti-friction roller 43.
- 45 Depending from the rock-shaft 14 is an operating arm 48, positioned on said shaft between fixed collars 51, 51 and provided with a suitably mounted roller 50 adapted to contact with pattern blocks 54 on the pattern-chain 55, so that said arm 48 and the rock-shaft 14 will be moved a greater or less distance, and in reverse directions, as determined by the lateral projection of the successive blocks and the action of a spring 53 arranged to retain the roller in contact therewith. The longitudinal movement of the rock-shaft 14 thus effected by the action of the moving pattern-chain, carries laterally all the embroidery-thread carriers 1 that are mounted on it, a distance of one or more needle spacings as determined by the chain blocks. In connection with this chain-block movement of the carrier I provide for effecting an additional lateral movement of the same; this being accomplished as shown

by means of a suitable cam mechanism arranged to actuate a shifting lever 44 bearing upon the roller 43 on the collar 40 so as to move the chain-mechanism bodily in one direction against the pressure of a spring 42 which tends to return it to normal position; the chain wheel shaft 39 to which said collar 40 is fixed being moved endwise and carrying with it not only the pattern chain mechanism, but the rock shaft 14 and the carrier frame.

To provide for cutting out the embroidery-thread when desired the rock-shaft 14 is arranged to be thrown into or out of gear with the operating lever 19 therefor, by means of a clutch mechanism comprising as shown a clutch pin 66 pivotally carried by an arm 65 on a suitably mounted slide rod 63, and movable with said slide rod through a guide-aperture in the cam-operated lever 20 into or out of engagement with an aperture 68 in said operating lever 19, so as to cause the latter to be moved with the cam-operated lever 20 or not as desired. The engaging and disengaging movement of the slide rod 63 is effected, as shown, by means of an arm 64 fixed thereto and slideable on the guide-rod 59, said arm 64 being connected with a clutch-operating slide 60 on rod 59, which slide is adapted to hold the clutch pin 66 in engagement with lever 19 when it is engaged by projections 61 on the chain blocks, while permitting release of such engagement when the chain projections are omitted.

In order to permit of throwing the clutch mechanism out of action when desired, independently of its automatic operation by the pattern-chain as described, I provide a hand-latch 88 on the arm 64, adapted to engage a keeper-recess 88^a so as to hold the clutch-pin 66 out of engagement with the lever 19; thereby stopping the rocking movement of the carrier rock-shaft 14 until said latch is released to throw the same under the automatic control of the pattern-chain.

The complete operation of my improved mechanism will be readily understood by reference to Fig. 4 which indicates diagrammatically the thread-carrier movements effected thereby in coöperation with the knitting mechanism to produce a single-needle stripe upon the fabric. In said diagrammatic view 1 represents the starting position of an embroidery-thread carrier rearward of the row of needles 21. The lateral movement of the carrier to the point *a*, which is effected by the action of the shifting lever 44 on the pattern-mechanism places the thread 30 in position to be turned over upon the divider 24 now in position above it, by the return lateral movement of the carrier to *c*; so that when the carrier is subsequently moved forward between the needles to *d*, then laterally to *e*, and finally

back again between the needles to its original position 1 to form a loop upon the single needle marked 21, in the manner previously described, said loop will be supported upon and accurately positioned in the notch of the divider so as to insure its proper showing on the face, or under side, of the fabric, after being carried down with the subsequently placed web thread 27 by the needle action. The preliminary lateral movements of the carrier to *a* and *c* thus serve to positively position the embroidery thread 30 vertically upon the needles 21 by wrapping it about the divider 24, while the rock-shaft 14 and the pattern-chain 55 effect the subsequent looping movements around the needle 21. This positive positioning of the embroidery thread upon the needles I have found to be practically essential to properly making a single-needle stripe. By wrapping this additional thread about a divider as described, preliminary to passing it around the needle, the resulting loop will be accurately placed at the proper height on the needle to insure its lying on top of the web thread when the latter is laid, so that a uniform showing of the embroidery thread on the face of the finished goods will be certainly secured. If a wider stripe than one needle is to be produced, or if figure designs in connection with the stripe are desired, the pattern-chain is arranged to correspondingly control the carrier movement from *d* to *e* without interference with the preliminary carrier movement described, and the stripping may likewise be automatically intermitted as desired. The embroidery carriers may be temporarily thrown out of action by means of the hand-latch 88, or the carrier frames may be entirely removed for convenience, as desired.

The thread-carriers 1 are made tubular to receive the thread, but are substantially diamond-shaped in cross-section so as to present forward and rearward knife-edges ^{1a} ^{1b} to the needles whereby spreading of the latter is insured for the proper passing of the carriers.

What I claim is:—

50 1. In a straight-bar knitting machine having coöperatively reciprocated knitting needles and dividers, an embroidery-thread carrier, means for reversely moving said carrier laterally to engage its thread upon a projected divider, and means for subsequently moving the same to pass the divider-engaged thread around an adjacent needle.

60 2. In combination with a straight-bar knitting machine, a coöperating embroidery-thread frame having bobbin-holders and thread-carriers, a rock-shaft having arms fixed thereto upon which said frame is pivotally mounted, means for rocking said shaft, means for independently rocking the pivotally mounted frame upon said arms,

and means for imparting endwise movement to said frame substantially as set forth.

3. In combination with a straight-bar knitting machine, a coöperating embroidery-thread frame having bobbin-holders and thread-carriers, a rock-shaft having arms fixed thereto upon which said frame is pivotally mounted, means for rocking said shaft, means for independently rocking the pivotally mounted frame upon said arms, pattern mechanism for imparting endwise movement to said frame, and means for jointly moving said pattern mechanism and frame endwise, substantially as set forth.

4. In a straight-bar knitting machine, an embroidery-thread-carrier mechanism comprising a rock-shaft and rocking mechanism therefor, a carrier-frame mounted on said rock-shaft, a pattern-chain mechanism arranged to longitudinally move said rock-shaft, and a stop mechanism operated by said pattern-chain mechanism to throw said rocking mechanism into or out of action.

5. In a straight-bar knitting machine, an embroidery-thread-carrier mechanism comprising a rock-shaft and rocking mechanism therefor, a carrier-frame mounted on said rock-shaft, a pattern-chain mechanism arranged to longitudinally move said rock-shaft, means for jointly moving said pattern-chain mechanism and rock-shaft, and a stop mechanism operated by said pattern-chain mechanism to throw said rocking mechanism into or out of action.

6. In a straight-bar knitting machine having an embroidery-thread carrier and means for moving the carrier-thread forward and backward between the needles, a pattern-chain mechanism comprising a pattern chain adapted to move the projected carrier laterally, and means for jointly moving said carrier and pattern-chain mechanism laterally before projecting said carrier.

7. In a straight-bar knitting machine having an embroidery-thread carrier frame and a rock-shaft upon which said frame is mounted, a depending arm on said rod, a slidably mounted rotary chain-wheel having a pattern-chain thereon engaging said arm to move said shaft longitudinally, and means for sliding said wheel and chain bodily.

8. In a straight-bar knitting machine having an embroidery-thread carrier frame and a rock-shaft upon which said frame is mounted, a depending arm on said rod, a rotary chain-wheel having a pattern chain thereon engaging said arm to move the rock-shaft longitudinally, and a clutch-operating slide operated by said pattern-chain to control the rocking action of said rock-shaft.

9. In a straight-bar knitting machine having an embroidery-thread carrier frame and a rock-shaft upon which said frame is mounted, a depending arm on said rod, a

slidably mounted rotary chain-wheel having
a pattern-chain thereon engaging said arm
to move said shaft longitudinally, means for
sliding said wheel and chain bodily, and a
5 clutch-operating slide operated by said pat-
tern-chain to control the rocking action of
said rock-shaft.

In testimony whereof, I affix my signa-
ture, in the presence of two witnesses.

FRIEDRIG H. STOEHREL.
